UNITED STATES PATENT OFFICE.

GEORGE E. MADISON, OF FLINT, MICHIGAN, ASSIGNOR TO GENERAL MOTORS CORPORATION, OF DETROIT, MICHIGAN, A CORPORATION OF DELAWARE.

DESIGN FOR A TOP FOR MOTOR-VEHICLES.

57,689.

Specification for Design.

Patented Apr. 26, 1921.

Application filed December 10, 1919. Serial No. 343,926. Term of patent 14 years.

To all whom it may concern:

Be it known that I, GEORGE E. MADISON, a citizen of the United States, and a resident of Flint, county of Genesee, and State of Michigan, have invented a new, original, and ornamental Design for a Top for Motor-Vehicles, of which the following is a specification, reference being had to the accompanying drawing, forming a part thereof.

The figure is a side elevation of a top for motor vehicles, showing my new design.

I claim:

The ornamental design for a top for motor vehicles, as shown.

In testimony whereof I hereunto affix my signature.

GEORGE E. MADISON.
